UNITED STATES PATENT OFFICE.

JOHN H. KILLION, OF CHICAGO, ILLINOIS.

BUILDING CONSTRUCTION.

Application filed December 9, 1921. Serial No. 521,131.

To all whom it may concern:

Be it known that I, JOHN H. KILLION, a citizen of the United States, residing at Chicago, in the county of Cook and State 5 of Illinois, have invented a new and useful Improvement in Building Constructions, of which the following is a specification.

This invention relates to building construction and the like and is fully described 10 in the following specification and shown in the accompanying drawings in which Figure 1 is a vertical section through a preferred form of the construction; Figs. 2 and 15 3 are modified forms of the same; Fig. 4 is a section on line 4 of Fig. 6, but showing plaster applied thereto; Fig. 5 is a section through the studding on the line 5 of Fig. 1; and Fig. 6 is a partial rear elevation of the inner or lathing strip.

20 This construction, as shown in Figs. 1 and 4, consists of a series of outer strips 10 which are folded inwardly at 11 at the bottom, and then given a reverse fold, 12, the latter serving to enclose the upper end 10^a 25 of the next lower strip 10 so as to be supported thereby. These strips lie horizontal one above the other as shown, and are held between studding 13. These studdings are rabbed at 14 to provide shoulders 15 30 against which the edges of the strips 10 are held by means of wood strips 16 which are secured to the studding 13 in any desired manner, as by means of nails 17.

It will thus be seen that the metal strips 35 10, held in this manner, serve to form a side wall or partition in themselves. Where, however, it is desired to add a coat of plaster to one side of this partition, I have provided an entire metal strip 18, which is preferably 40 corrugated as shown in Fig. 4, and provided with a series of perforations 19, through which the water may pass to form a suitable lock. The edges 18^a and 18^b of the inner strip are flattened so as to engage 45 the fold 11 on the bottom and the fold 12 of the next higher outer strip, thereby maintaining the inner and outer securely locked together. It is necessary, as shown in Fig. 5, with the inner strip 18 made shorter than 50 the outer strip 10 so as to provide space for the wooden strip 16.

Mortar 20 may then be applied as shown in Fig. 4, which will be pressed by the trowel through the openings 19 forming 55 keys 21, whereby the mortar is firmly held in place when it stays.

In Fig. 2 is shown a modification 1, having a continuous outer strip 22, which is given a series of bends forming transverse folds 23 at regular intervals. Inner strips 18, similar to those previously described, 60 may be inserted in these folds so as to be supported thereby. When mortar is applied to these inner strips, which are also supplied with suitable perforations or other means for holding the mortar, the upper edges of these will be held by the mortar which is firmly locked thereto, and to the next upper strip. 65

In Fig. 3 is shown still another modification in which each inner strip 18 is locked in an outer strip 24, which has folds 25 and 26 formed by folding inwardly the metal upon the edges of the strip upon the same side thereof. The edges of these outer strips 70 are guided, as previously described, between the shoulders 15 and the studding, and wooden strips 16. The lower corrugations of the inner strip rest upon the top of the next succeeding outer strip, as shown in 75 Fig. 3, and the whole is still more securely fastened together by means of mortar which is then applied thereto in the same manner as shown in Fig. 4.

While I have shown and described but a few embodiments of my invention, it is to be understood that it is capable of many modifications. Changes, therefore, in the construction and arrangement may be made which do not depart from the spirit and scope of my invention as disclosed in the appended claims in which it is my intention to cover all novelty inherent in the invention as broadly as possible in view of the prior art. 85

What I regard as new and desire to secure by Letters Patent, is:

1. A building construction comprising a series of horizontally arranged overlapping strips of sheet metal, the lower edges of said strips being folded inwardly, perforated lath members supported by said inwardly folded lower edges of said strips and guides for holding said strips in alignment. 100

2. A building construction comprising a series of horizontally arranged overlapping strips of sheet metal, the lower edges of said strips being folded inwardly, perforated lath members supported by said inwardly folded lower edges of said strips, each strip 105 being supported by the next lower strip and guides for holding said strips in alignment. 110

3. A building construction comprising a series of horizontally arranged overlapping strips of sheet metal, the lower edges of said strips being folded inwardly, and perforated lath members supported by said inwardly folded lower edges of said strips, said strips being confined at their ends between guides. 35
4. A building construction comprising a series of horizontally arranged overlapping strips of sheet metal, the lower edges of said strips being folded inwardly, and perforated lath members supported by said inwardly folded lower edges of said strips, said strips being confined at their ends between guides, 40 each strip being supported by the next lower strip.
5. A building construction comprising a series of horizontally arranged overlapping strips of sheet metal, the lower edges of said strips being folded inwardly, and perforated lath members supported by said inwardly folded lower edges of said strips, said lower edges being reversely folded to form a groove which passes over the upper edge of the next lower strip, said strips being confined at their ends between guides. 45
6. A building construction comprising a series of horizontally arranged overlapping strips of sheet metal, the lower edges of said strips being folded inwardly, and perforated lath members supported by said inwardly folded lower edges of said strips, 50
- 20
- 25
- 30
- 35
- 40
- 45
- 50
- 55
- 60
- 65
7. A building construction comprising an outer strip and an inner strip secured thereto, said inner strip being corrugated, some of said corrugations touching said outer strip whereby each reinforces the other, said strips being confined at their ends between guides.
8. An article of manufacture comprising a strip of sheet metal, the lower edge of said strip being folded inwardly and having a portion adapted to overlap the upper edge of another similar strip, and perforated lath members supported by said inwardly folded lower edges.
9. An article of manufacture comprising a strip of sheet metal, the lower edge of said strip being folded inwardly and having a portion adapted to overlap the upper edge of another similar strip, and perforated lath members slidable in said inwardly folded lower edges.
10. An article of manufacture comprising an outer strip having inwardly turned flanges and an inner strip slid endwise between said flanges, said inner strip being corrugated, some of said corrugations touching said outer strip whereby each reinforces the other.

JOHN H. KILLION.
